UNITED STATES PATENT OFFICE

97,179

DESIGN FOR A TEXTILE FABRIC, OR SIMILAR ARTICLE OF MANUFACTURE

Gertrude Deist, New York, N. Y.

Application January 10, 1935, Serial No. 54,791

Term of patent 3½ years

To all whom it may concern:

Be it known that I, Gertrude Deist, a citizen of the United States and a resident of the Borough of Manhattan, city, county, and State of New York, have invented a new, original, and ornamental Design for a Textile Fabric, or Similar Article of Manufacture, of which the following is a specification, reference being had to the accompanying drawing, forming a part thereof.

The figure of the drawing is a plan view of a piece of textile fabric showing my new design, in which the background is of a single solid color and the design elements thereon are of another and sharply contrasting color, the said design elements being in bold relief with respect to the said background.

I claim:

The ornamental design for a textile fabric, or similar article of manufacture, as shown and described.

GERTRUDE DEIST.
